UNITED STATES PATENT OFFICE.

HENRY P. BRUMELL, OF NEW YORK, N. Y., ASSIGNOR TO AJAX ELECTRIC HAMMER CORPORATION, OF NEW YORK, N. Y., A CORPORATION OF NEW YORK.

POWER-DRIVEN HAMMER OR RIVETER.

Application filed January 20, 1926. Serial No. 82,466.

This invention relates to power driven hammers or riveters.

Prior power driven hammers or riveters with which I am familiar do not possess the 5 rigidity and endurance desired in practice, the pounding and racking reciprocations of the plunger often impairing or wrecking the unit soon after it is put in use. For example the housing for the drive and the plunger is 10 peculiarly subject to the racking operations and the plunger guide is often thrown out of alinement with the drive housing with resultant strains being put thereupon which approach the rupturing point, and this is 15 particularly true of that type of hammer including a rotary motor, crank pin and double-cam drive mechanism wherein it is essential for satisfactory operation and wear that the crank pin drive and the plunger 20 occupy a predetermined fixed and practically unaltering relation with reference to each other throughout the intended life of the hammer. One object of the invention, therefore, is a novel casing construction and 25 assembly for housing a hammer plunger and drive mechanism therefor including a special construction of guide and casing for the reciprocating hammer plunger and plunger drive which is peculiarly characterized by 30 its rigidity and its ability to withstand the most severe operating conditions without premature impairment. A further object of the invention is a construction of this character which may be readily and quickly 35 assembled into a rigid non-yielding structure and disassembled with equal readiness and facility. A further object of the invention is a novel construction and arrangement of drive mechanism between the 40 reciprocating hammer element and the rotary motor which lends itself to ready and quick assembly. A still further object of the invention is a casing and drive assembly for hammers of the above indicated character of simple construction and minimum 45 parts whereby the manufacture thereof on a quantity production basis is facilitated and may be economically effected.

For a better understanding of the invention, reference may be had to the accompanying drawings forming a part of this application wherein:

Fig. 1 is a longitudinal sectional view through the hammer,

Fig. 2 is a view at right angles to Fig. 1

with certain parts removed and showing the drive mechanism including the hammer element, and

Fig. 3 is an exploded view illustrating the assembly and disassembly of the hammer. 60

Referring to the drawings where like numerals designate similar parts throughout, I have illustrated my invention as embodied in a hammer including an electric motor 1 driving a hammer element 2. The motor 1 65 is journaled and carried within the casing parts 4 and 5, the casing part 4 having an extension 4' which cooperates with a cap or cover member 6 to house the intermediate driving mechanism and to anchor the guide 70

7 for the plunger or head 3 of the hammer element rigidly in alined position. The guide 7 may be of any suitable or desired shape, but in the particular embodiment illustrated it is of hollow nozzle-like construction and has on its inner end or base 75 a heavy circular flange 8. The casing parts 4' and 6 have corresponding mating arcuate recesses 9 for the reception of the circular flange 8 when the plunger guide is gripped 80

and held within the socket 9' formed between the outer ends of the casing parts 4' and 6. The latter are thickened and made unusually heavy in the vicinity of the recesses 9 and the circular flange 8 to firmly 85

and rigidly hold the nozzle-like guide 7 in operative alined position. The drive for the hammer element 2 and plunger 3 includes a double cam 10 and 11 carried by 90

the hammer element and a rotary disc or 95 turret 12 carrying a crank pin 13 which alternately functions with the cams 10 and 11 to reciprocate the hammer element 2 back and forth. The double cams 10-11 are formed in a slide block and the latter is preferably formed integrally with the hammer element 2-3. The slide block which includes the cams 10-11 slides back and forth on or parallel to the disc 12 with its straight sides engaging a pair of roller 100

guides 21, 22 which are disposed on opposite sides thereof, and in the relative position shown to take up side thrust and render the reciprocation of the hammer element 2 as frictionless as possible. The disc or turret 105 12 forms a part of a unit including a circular ball bearing ring 14, the vertical stub shaft 15 upon which the disc 12 is mounted and the bevel gear 16. The lower end of the shaft 15 is carried by a ball bearing unit 110

17, the latter being mounted in a suitable recess formed in the bottom of the extension 4' of the casing. The rotary unit including the disc 12, the ball bearing unit 14 and the 5 shaft 15 is readily assembleable or insertable into operative position by removing the cap or casing part 6 and lifting the guide 7 and the hammer element 2 from the casing 4'. The bevel gear 16 automatically meshes 10 with a smaller bevel 18 on the end of the motor shaft when the disc unit 12 is inserted in position. As indicated above, the hammer element 2 together with its double cam drive 10 and 11 slides back and forth 15 across the upper surface of the disc unit 12 and the ball bearing unit 14, an opening 23 being provided between the mating end walls of the casing parts 4' and 6 to accommodate the reciprocating hammer element. 20 Fig. 3 indicates the facility with which the assembly and disassembly of the essential elements of the hammer may be effected. The rotary disc or turret 12 and the parts carried thereby are lowered into position 25 within the casing first with the lower end of the stub shaft 15 supported by the ball bearing unit 17, the extension 4' of the casing being adapted to receive this unit in a snugly fitting manner. The hammer element 2 may then be inserted within the plunger guide 7 and these two elements may 30 then be assembled into position with the circular flange 8 resting in the arcuate recess 9 formed in the thickened and strengthened part of the extension 4' and with the 35 double cam 10, 11 straddling the driving crank pin 13 and disposed between the roller guides 21, 22. The parts are then in operative position and the casing or cap part 6 40 may then be assembled into mating relation with the extension part 4' to firmly grip and rigidly hold the guide 7 in alignment with the reciprocating hammer element 2 with the plunger 3 guided in the hollow 45 chamber formed therein. The casing parts 4' and 6 may be fastened together in any suitable manner, the guide 7 with its cylindrical flange 8 formed on the base thereof being rigidly retained in operative position 50 without the necessity of any securing bolts or other fastening means which would be more or less subject to wear and breakage incident to the hammering operation. Even when the plunger 3 strikes the shoulder 25 55 of the nozzle carrying the tool, the shock is distributed over the entire side surface of the flange 8 and the corresponding surface of the arcuate recess 9, and these parts are designed as described above to withstand 60 these shocks when distributed in that manner. The rigidity and permanency of the structure are not dependent upon screw threads to receive and withstand the hammer thrusts, and there are no bolt heads to 65 interfere with the operator's hand during

operation. The cap or casing 6 is observed to slightly overlap the ball bearing ring unit at 19 and thereby to firmly hold and retain the disc 12 and its unitary parts firmly in position. 70

The motor 1 may be assembled into position by simply inserting it longitudinally within the cylindrical casing part 4 with the shaft and gear 18 projecting into the extension 4' and then bringing the end casing part 5 into abutting relation with the part 5 to form an end housing for the motor and to carry the bearing unit therefor. Either the motor or the bearing unit including the gear 16 may be inserted into position first, the gears 16 and 18 automatically meshing with each other in either event. The casing part 5 includes a hollow handle part 5' formed integrally therewith as a hand hold for the operator of the hammer. The 80 drive chamber formed by the casing parts 6 and 4' is provided with openings for inspection and for the introduction of suitable lubricant, suitable screw threaded plugs 20 being utilized for closing these openings. 90

In the construction illustrated the entire casing consists of four parts 4, 5, 6, 7 which may be manufactured on a quantity production basis as for example by casting, with the corresponding reduction in cost of production, and the small number of parts together with their simplicity in construction contribute to a ready and quick assembly and disassembly for inspection and replacement of parts. 100

Having thus described my invention, what I claim and desire to protect by Letters Patent is:

1. In a power driven hammer including a reciprocable hammer element and a drive mechanism directly connected therewith, a nozzle-like guide for the reciprocating hammer element and a pair of mating casing members adapted to enclose the drive mechanism for the hammer element and being of a construction to firmly grip and rigidly hold said guide in operative aligned position with respect to the reciprocable hammer element when the casing parts are fastened together. 115

2. In a power driven hammer including a reciprocable hammer element and a drive therefor, a guide member having a guide chamber therein for the reciprocable hammer element and a lateral projection on one end thereof, and a pair of casing mating members adapted to house the driving mechanism for said hammer element and containing a retaining recess for the reception of the projection on said guide member when the casing parts are assembled together, whereby the guide member is rigidly supported in operative alignment with the reciprocating hammer element. 125

3. In a power driven hammer including a 130

- reciprocable hammer element and a drive therefor, a nozzle-like guide having a guide chamber therein for the reciprocable hammer element and a circular laterally projecting flange on one end thereof, and a pair of mating casing members adapted to house the driving mechanism for said reciprocating hammer element, including a socket portion disposed outside of the drive chamber, together with arcuate recesses to receive said nozzle-like guide with its circular flange and to hold the same rigidly in alinement with said reciprocating hammer element when the casing parts are brought into mating relation.
4. In a power driven hammer including a reciprocating hammer element and a drive unit therefor, a pair of casing members adapted to house said drive unit, said casing members having heavy rigid extensions which are adapted to form a socket for the reception of a nozzle-like guide for the reciprocating hammer element, said hollow guide projecting beyond said rigid extensions and having a part disposed within said socket and rigidly and fixedly retained in alined position by said cooperating mating casing members when the latter are fastened together.
5. In a power driven hammer, a pair of mating casing members which are adapted to house a driving unit, said casing parts having outside the chamber formed therebetween integral heavy mating extensions adapted to form therebetween when assembled a cylindrical socket for the reception of a nozzle-like guide member for the reciprocating hammer element, said heavy extensions also including mating arcuate recesses, and a nozzle-like guide member disposed within the socket formed between the heavy extensions and having a heavy circular flange retained with the mating arcuate recesses of the casing parts, whereby the nozzle-like guide member is gripped and rigidly retained in operative alinement.
6. In a power driven hammer a rotary drive unit including a rotating driving crank pin, a reciprocable hammer element having a double cam functioning alternately with the crank pin to reciprocate the hammer element in a plane parallel with the plane of rotation of the crank pin, a pair of mating casing members which are adapted when assembled to house said rotary driving unit with an opening therethrough for the reciprocation of the hammer element, said casing parts having outside the chamber formed therebetween integral heavy mating extensions forming therebetween a cylindrical socket chamber and a hollow nozzle-like guide member for the reciprocating hammer element having a part rigidly carried within said socket and projecting beyond the mating extensions for guiding the reciprocating hammer element therealong.
7. In a power driven hammer including a reciprocable hammer element and a drive unit therefor, a guide for the reciprocating hammer element, a pair of mating casing members inclosing the drive unit and carrying said guide, one of said mating members being constructed to receive the drive unit in operative position and the other being adapted to engage the drive unit when brought into mating relation with the corresponding mating member and thereby retain the drive unit in operative relation with respect to the reciprocating hammer element.
8. A hammer of the character set forth in claim 7 wherein the guide for the reciprocating hammer element is carried within a socket formed between the mating members and includes a circular flange rigidly retained in a corresponding annular recess formed in the two mating members.
9. A power driven hammer including a power motor housed in a casing divided transversely thereof, one of said transversely divided parts having a longitudinally divided part including an integral extension for receiving and holding an intermediate drive, a guide member for the reciprocating element carried by said extension and the mating member for the integral extension enclosing the intermediate drive and gripping the guide member when brought into mating relation with the integral extension.
10. A power driven hammer including a reciprocable hammer element and drive therefor, a pair of mating casing members adapted to enclose the drive mechanism and the reciprocable hammer element, a nozzle like guide having an enlarged central longitudinal chamber at its rearward end for the reception of a part of the reciprocable hammer element and having a smaller guide opening through the outermost end thereof and communicating with the other chamber, the smaller chamber being adapted to receive a suitable tool, and the mating members being of a construction to firmly grip and rigidly hold said nozzle like guide in operative alined position with respect to the reciprocable hammer element when the casing parts are fastened together.

In testimony whereof, I have signed my name to this specification.

HENRY P. BRUMELL.
